UNITED STATES PATENT OFFICE

CORA P. WEAVER, OF ALHAMBRA, CALIFORNIA

AUTOMOBILE CURTAIN

Application filed September 14, 1926. Serial No. 135,305.

This invention relates to improvements in automobile curtains and more particularly to curtains for the side doors of preferably closed machines.

One of the objects of my invention is to provide a simple, efficient and inexpensive device of this character wherein is embodied the desirable feature of vertical adjustment of the curtain relatively to the window for the purpose of screening effectually the rays of sun that oftentimes project thru the side window upon the driver or other occupants, causing eye strain or embarrassment.

Another object of my invention is to provide a novel auto curtain which can be readily moved up and down relatively to any side window of the machine, so that it may be positioned and retained in adjusted position, and thereby serve to screen sunlight from affecting the eyes of the driver.

A still further object of my invention is to provide, in a device of the character described, a green colored transparent panel or more than one such panel on the side adjustable curtain, so while the sun-light may find its way thru this panel it will not cause any discomfiture to the occupants of the front seat.

At different times of the day the sun is in different positions so that streaks of sunlight project themselves into the side windows of autos at different points, resulting in eye-strain, unusual warmth or fatigue; as the sun rays are concentrated always at the same point for a considerable time the effulgence of these rays often causes eye fatigue and eye strain, interfering with the proper handling of the car by the driver. To overcome this my invention of curtain is designed to afford a quickly-positionable device for allowing the sun rays to be screened at various points, so the harmful effects of the sunlight will be eliminated.

With the above and other objects in view my invention consists in the combination, arrangement and details of construction disclosed in the drawings and specifications, and then more particularly pointed out in the appended claim.

In the drawings, wherein similar refer-

ence characters designate similar parts throughout the respective views,

Figure 1 is a side view, of a fragmentary automobile showing my invention in position thereupon,

Figure 2 is a view similar to Figure 1 but showing another form of my invention mounted in position,

Figure 3 is a plan, partly sectional view of parts shown in Figure 2,

Figure 4 is a vertical sectional view showing parts of Figure 2,

Figure 5 is a longitudinal sectional view of parts shown in Figure 1,

Figure 6 is a top plan view of still another form of my invention.

Referring to the drawings, which are merely illustrative of my invention A designates the side of an automobile frame or body, preferably of the closed-car type of design in which side windows are provided the glass panels of which may be caused to disappear at the will of the operator.

In Figure 1 I show one form of my invention consisting of the strips, preferably made of fabric or flexible material, designated 1 and 2 and located at the opposing ends of the open window B, so as to flank said window. Designed to movably engage slidably and adjustably upon strips 1 and 2 is a fabric automobile curtain of desirable make designated 4, having gathers or loops 5 and 6 formed terminally or at opposite ends of the curtain 4. It will be seen that the strips 1 and 2 may be secured upon the body of the car in any approved manner preferably by means of glove fasteners designated broadly 3, so that these strips may be removed at random from the machine. The same type of fasteners may be employed which are now used to attach the side curtains to a machine.

The curtain 4 carries one or more transparent panels 8 as may be desired and I preferably will make the panel green in color so that even if the rays of the sun may enter the machine the same will exert no harmful effect upon the eyes of the occupants, especially the driver of the car. Any other color may, with like advantage be used. From Figure 5 it will be seen that each panel 8 is

secured in cleats or retainers 7 carried by or secured to the curtain. The fabric portions of the curtain may terminally be folded back to present overlapping thicknesses of material as at 6'.

5 In Figure 2 I disclose a different form of my invention of adjustable curtain wherein use is made of preferably metal strips 9 and 10 instead of the fabric strips 1 and 2, and 10 these strips are secured at their upper and lower ends to the body A of the machine by means of fasteners 17. The intermediate major portions of these strips 9 and 10 are offset or deflected as at 9' so as to position itself 15 in spaced relation with respect to the adjacent surface of the window, as illustrated in Figure 4. The intermediate offset portions of these strips 9 and 10 are formed with elongated slots 11 in which project the usual 20 thumb bolts 13, which may slide in these slots to adjust the curtain 14 in any desired vertical position, this curtain also extending across the opening B. The jamb nuts 13' clamp the curtain in adjusted position. 25 The thumb bolts 13 pass thru the arms 12 formed integrally upon end pieces 10 of the curtain 14, and are disposed parallel to said end-pieces being connected to the latter by the rightangularly-disposed integral lugs 30 18 formed upon the end pieces and serving to space the arms 12 outwardly of the window frame a distance sufficient to allow the arms to slidably overlap the strips 9 and 10. In this way a mechanical device is obtained 35 which will effectively position the curtain in the desired adjusted position.

Another form of curtain holding device suitable for use in connection with the frame shown in Figure 4 is shown in Figure 6 which 40 consists of an all-metal curtain 20 of proper width having its ends formed with rightangular lugs 21 with arms 22 similar to arms 12; openings 15 and 16 in this frame correspond to openings 15 and 16 of Figure 2 45 carrying the green transparent panels; cleats 24, 25 secure the green transparent panels 23, and 26 in position opposite openings 15, 16 in the frame shown in Figure 6. In Figure 2 C is the fender, E the side door.

50 From the above it will be seen that I have provided a simple contrivance for adjustably mounting in removable relation upon the side window of an auto a curtain which will screen the sun rays, and as the sun disappears 55 the curtain can be moved higher and higher.

I claim all variations falling within the purview of the appended claim.

What I desire to claim and seek by Letters Patent is:—

60 In combination with a frame having a window opening, a pair of vertically disposed fabric strips having only their opposing ends secured to the frame and their main body portions overlying said frame along adjacent 65 window opening edges, a fabric curtain hav-

ing transverse loops formed at its opposing ends, mounted slidably and frictionally in embracing relation upon said strips, said curtain bridging the full length of said window opening and being of a width narrower than 70 that of the window opening to allow it to be raised or lowered vertically of the window, and a colored transparent panel carried by said curtain.

In witness whereof, she has hereunto set 75 her hand this twenty eighth day of August, 1926.

CORA P. WEAVER.
